PACKING

Wade E. Sackner, Grand Rapids, Mich., assignor
to Grand Rapids Fibre Cord Company, Grand
Rapids, Mich.

Application August 16, 1939, Serial No. 290,530

1 Claim. (Cl. 154—43)

This invention relates to improvements in packing.

This invention relates to packing cords suitable for use in the millinery trade for making rolls in hats and the like. Such material must be light in weight and preferably must have a smooth outer surface so that it will not disfigure material stretched over it. It must be elastic and preferably inexpensive.

Heretofore such cords have been made of cotton or the like formed to cylindrical form and retained either by wrapping threads or by a stitched fabric cover. It is expensive to apply stitched fabric covers and if wrapping threads are employed the sheer materials used over the cord are disfigured by the indentations and raised portions made on the surface of the cord by the wrapping threads.

The objects of the present invention are:

First, to produce a new and improved packing cord suitable for use in the millinery trade or the like.

Second, to produce such a cord which is inexpensive, light in weight, and which has a smooth, even surface which will not disfigure a fabric stretched thereover.

Other objects and advantages pertaining to details and economies of construction and operation will appear from the description to follow. A preferred embodiment of my invention is illustrated in the accompanying drawing, in which:

Fig. 1 is a perspective view of the core employed in my new packing cord showing how it is formed.

Fig. 2 is a perspective view of the cord with the wrapping cover open to show the manner of application thereof.

Fig. 3 is a perspective view showing a section of the finished cord.

The finished cord 1 is made up of a core 2 and an outer cover 3.

The core 2 is substantially cylindrical in form and is made up of sheets of cellulose crepe wadding which is sold commercially under the trade name "Kimpak." These sheets are compressed to cylindrical form and the outer covering is applied thereto to hold the core in its form.

The outer covering of my improved cord is made up of a plurality of plies of sheet cellulose crepe wadding. This material is lace-like in form and apparently has no tensile strength. I have found, however, that a plurality of plies of the material form a highly satisfactory cover for a cord such as that to which this invention relates. The material has considerable tensile strength and has a very desirable feel in the finished product. It may be applied to form a smooth outer cover at a minimum of expense. I prefer to employ 10-ply cellulose wadding.

After the core is compressed to form, the covering which consists of a strip made up of a plurality of sheets of the cellulose crepe wadding is wrapped around the core and the edges are joined by a layer 4 of adhesive which may be glue or latex. In order to make a smooth core, I fold the outer overlapping edge 5 inwardly as shown in Fig. 2 and apply the adhesive between the surface of the in-folded edge and the surface 6 of the inner edge of the cover. The adhesive extends to the surface of the cord so that a completely smooth covering results.

The finished cord is extremely light in weight and is resilient. It retains its form even after stretching and is highly satisfactory because of these desirable qualities. The smooth outer surface does not distort the fabric stretched over the cord so that the material does not interfere with the decorative effects desired in the millinery trade. The material may be made very inexpensively.

I have described and shown a preferred form of my invention and define the same in the claim.

Having thus described my invention, what I claim as new and desire to secure by Letters Patent is:

A packing cord consisting of a substantially cylindrical core of compressed cellulose crepe wadding, and a smooth outer cover therefor comprising a sheet formed of substantially 10 or less plies of sheet cellulose crepe wadding surrounding said core and retaining it in form, the edges of said sheets overlapping and joined by a layer of adhesive.

WADE E. SACKNER.
